UNITED STATES PATENT OFFICE.

PAUL A. SCHUCHART AND GOVEURNEUR GRAHAM BROWN, OF NEW YORK,
N. Y., ASSIGNEES TO COMPOSITE PILE CONSTRUCTION COMPANY, OF
NEW YORK, N. Y., A CORPORATION OF NEW YORK.

SHEET-PILEING.

No. 850,496.

Specification of Letters Patent.

Patented April 16, 1907.

Application filed February 23, 1906. Serial No. 302,404.

To all whom it may concern:

Be it known that we, PAUL A. SCHUCHART, a subject of the Crown of Austria, and GOVEURNEUR GRAHAM BROWN, a citizen of the United States, and residents of the borough of Brooklyn, in the city and State of New York, have invented a new and useful Improvement in Sheet-Piling, of which the following is a specification.

- 10 Our invention relates to an improvement in sheet-piling, and has for its object to provide a composite sheet-piling comprising alternating wood planks and metal beams which are interlocked in a very simple and effective manner, so as to form a strong and water-tight wall suitable for all purposes to which sheet-piling is adapted—such, for instance, as in the construction of sea-walls, docks, pier-foundations, &c.
- 15 A further object is to provide a composite sheet-piling which can be set up at a less expense than has heretofore been possible, the number of parts being reduced to a minimum.

In the accompanying drawings, Figure 1 represents a section of our improved composite sheet-piling in top plan. Fig. 2 is a side view of the same, portions of the piling intermediate the top and bottom being broken away; and Fig. 3 is an enlarged horizontal section through one of the metal beams and adjacent portions of two of the wood planks, showing more clearly the interlocking of the same irrespective of the angular position of the planks with respect to each other within a limited scope.

The sheet-piling is composed of alternating wood planks and metal beams 1 and 2. The wood planks may be provided at their lower ends with sharpened points 3 for facilitating the driving of the planks into the ground.

Each metal beam is shown as comprising a central longitudinal web 4, from one edge of which two opposite long jaws 5 extend and from the other edge of which two opposite short jaws 6 extend. The opposite jaws of each beam have portions thereof embedded in the opposite faces of the adjacent planks. In the present instance we have shown this result as accomplished by turning the edges of each pair of jaws 5 and 6 inwardly toward each other, the distance between the edges of said jaws being less than the thickness of the wood plank.

The reason for making the jaw 6 shorter than the jaw 5 is to permit the wood plank to be interlocked with the metal beam irrespective of its angular position with respect to the same within a limited scope.

When the piling is set up, the edges of each pair of jaws 5 and 6 of the metal beams will be embedded in the opposite faces of each wood plank 1, with the side edge of the plank spaced from and inclosed by the said jaws and the web 4, so that the side edge of the plank is effectually protected, and also a cavity is formed within the metal beam.

The tendency of the wood to swell when the piling is used in connection with hydraulic work will more fully and completely interlock the wood planks and metal beams, and thus make the joints waterproof.

If it is desired to tighten the piling, the spaces around the edges of the wood planks within the metal beams may be filled with sand, clay, cement, or other suitable material 7.

By constructing a sheet-piling as herein set forth the use of additional means for interlocking the planks and beams is obviated, and it will be seen that wood planks of ordinary construction not specifically shaped may be used, the edges of the planks being effectually protected by the metal beams. Also by turning the edges of each pair of jaws inwardly toward each other a cavity is formed around the side edge of the wooden plank, and by making one jaw shorter than the other the plank may be turned at an angle to the beam, so that a corner may be turned in the sheet-piling without the use of specially-shaped beams or planks therefor.

What we claim is—

1. A composite sheet-piling comprising alternating wood planks and metal beams arranged longitudinally and interlocked together, the metal beams being provided with jaws having portions thereof embedded in the opposite faces of the wood planks along their side edges.

2. A composite sheet-piling comprising alternating wood planks and metal beams arranged longitudinally and interlocked together, the metal beams being provided with pairs of jaws embedded in the opposite faces of the wood planks for protecting the edges of the planks along their side edges.

3. A composite sheet-piling comprising al-

- ternating wood planks and metal beams interlocked together, the metal beams being provided with pairs of jaws embedded in the opposite faces of the wood planks the parts being so arranged as to leave cavities around the edges of the planks within the said beams.
4. A composite sheet-piling comprising alternating wood planks and metal beams interlocked together, the metal beams being provided with pairs of jaws embedded in the opposite faces of the wood planks the parts being so arranged as to leave cavities around the edges of the planks within the said beams and a filling for said cavities.
- 15 5. A composite sheet-piling comprising alternating wood planks and metal beams arranged longitudinally and interlocked together, the metal beams being provided with pairs of jaws having their edges embedded in the opposite faces of the wood planks along their side edges.
- 20 6. A composite sheet-piling comprising alternating wood planks and metal beams interlocked together, the metal beams being provided with pairs of jaws having their edges embedded in the opposite faces of the wood planks, one of the jaws of each pair being shorter than the other jaw.

7. A composite sheet-piling comprising alternating wood planks and metal beams arranged longitudinally and interlocked together, the metal beams being provided with pairs of jaws having their edges turned inwardly and embedded in the opposite faces of the wood planks along their side edges.

30 8. A composite sheet-piling comprising alternating wood planks and metal beams arranged longitudinally and interlocked together, each metal beam being provided with two pairs of jaws having their edges embedded in the opposite faces of two adjacent wood planks along their side edges.

35 In testimony that we claim the foregoing as our invention we have signed our names, in presence of two witnesses, this 22d day of December, 1905, and February 9, 1906, respectively.
